UNITED STATES PATENT OFFICE.

CHARLES E. LINDSAY, OF ALBANY, AND CLINTON V. OGBIN, OF NEW YORK, N. Y.;
CAROLYN P. LINDSAY EXECUTRIX OF SAID CHARLES E. LINDSAY, DECEASED.

MEANS FOR LOADING AND UNLOADING CARS.

Application filed January 31, 1922. Serial No. 533,003.

To all whom it may concern:

Be it known that we, CHARLES E. LINDSAY and CLINTON V. OGBIN, both citizens of the United States, and residents, respectively, of Albany, in the county of Albany and State of New York, and the city of New York, borough of the Bronx, in the county of Bronx and State of New York, have invented a new and Improved Means 10 for Loading and Unloading Cars, of which the following is a full, clear, and exact description.

The present invention relates to new and useful improvements in means for loading 15 and unloading cars, and it pertains more particularly to a device of this character especially adapted for handling railway ties.

It is one of the primary objects of the invention to construct a device of this character 20 so that it is capable of use with cars of various types but more particularly for use with cars of the so-called gondola type.

It is a further object of the invention to construct a device of this character so that 25 it may be readily attached to and detached from cars, and, at the same time, will be securely held in operative position on the car.

It is a further object of the invention 30 to provide means whereby the improved device may be operated from the air-line of the car.

It is a further object of the invention to construct a device of this character which 35 is adjustable in order to meet varying operating conditions.

With the above and other objects in view, reference is had to the accompanying drawings, in which

Figure 1 is a view in elevation partly in section, of the improved device in operative position;

Fig. 2 is a detail sectional view of the lower portion of the cylinder showing the 45 piston at the lower end thereof;

Fig. 3 is a horizontal sectional view taken on the line 3—3 of Fig. 1;

Fig. 4 is a detail sectional view partly broken away, of the upper portion of the 50 device;

Fig. 5 is a horizontal sectional view taken on the line 5—5 of Fig. 4;

Fig. 6 is a detail sectional view of the valve mechanism;

Fig. 7 is a horizontal sectional view of the relief valve of the cylinder.

Fig. 8 is a detail sectional view.

Referring more particularly to the drawings, the reference character 10 designates a freight car of ordinary construction and 60 of the type with which the device illustrated in the present invention is adapted for use.

The device comprises a main tubular member 11 and pivotally secured to the 65 lower end thereof is a cam or the like 12. Mounted on the cam 12 is an arm or bar 13, and said bar carries a block 14 adapted for engaging the sill 15 of the car 10. The block 14 has a serrated portion 16 adapted 70 to engage a plurality of rack teeth 15 on the bar 13 in order that the block 14 may be adjusted longitudinally of the arm 13. The cam 12 is mounted upon a shaft 17, and secured to said shaft 17 is a lever 18 provided with an operating handle 19. By this construction it is apparent that as the operating lever 18 is moved to position above the cam or opposite to that shown in Figure 1, the bar 13 will be reciprocated to the 75 left in Figure 1, and the block 14 will disengage the sill 15. When, however, the device is positioned for use with the operating lever in the position shown in Figure 2 and the block 14 is adjusted relatively to the 80 bar 13 to engage the sill 15 of the car 10, it is apparent that if the operating lever 18 be moved to the position shown in Fig. 1, the cam will serve to cause the block 14 to bite 85 or engage the sill 15 to securely clamp the 90 tubular member in position with respect to the car.

The reference character 20 designates a collar surrounding the tubular member 11, and said collar has a plurality of oppositely 95 disposed arms 21. Each of the arms 21 is provided with a block of wood or other suitable material 22 adapted to engage the side of the car to prevent rocking of the tubular member 11 under operative conditions. These blocks are made in various sizes and are mounted in such a manner as to be interchangeable. As shown in Figure 3, the collar 20 is provided with a pin or

similar member 23 adapted to engage the tubular member 11 to maintain the collar 20 in adjusted position thereon.

A cylinder 24 is adapted to be received 5 within the tubular member 11, as more clearly shown in Figures 1 and 2. This cylinder is provided with a plurality of recesses 25 and carried in the housing 26 formed on the tubular member 11, is a 10 plurality of pawls 27 adapted to engage the recesses 25 to maintain the cylinder 24 in adjusted position relative to the tubular member 11. Mounted within the cylinder 24 and adapted to reciprocate longitudinally 15 thereof, is a piston 28, and said piston 28 carries a piston rod 29, the upper end of which is provided with a pulley 30. As more clearly shown in Figure 4, this pulley 30 is mounted in a yoke 31, and the pulley 20 yoke 31 is swivelled to the upper end of the piston rod 29 as designated by the reference character 32.

As more clearly shown in Figure 6, a valve housing 33 is secured to the upper end 25 of the cylinder 24, and leading into said valve housing are two three-way valves 35, said three-way valves being arranged in diametrically opposite relation one to the other. Mounted in the upper portion of the 30 valve housing 33 at diametrically opposite points are two check valves 36 and said check valves 36 are adapted to permit of fluid entering the cylinder therethrough but are adapted to seat upon the exhaust or 35 fluid from the cylinder 24. Each of these check valves is provided with a bleed port 37, the purpose of which will be hereinafter more fully described.

Leading from the valve housing 33 to 40 the interior of the cylinder at a point spaced from the upper end of the cylinder are passages 38, of which but one is shown in Figure 6, and these passages 38 are positioned one opposite each of the three-way 45 valves 35. Each of these three-way valves 35 has a nozzle or the like 39, by means of which a hose or other suitable line 40 may be attached.

The valve housing 33 is formed with a 50 partition 41 which closes the upper end of the cylinder and carried by said partition 41 is a stuffing box 42 through which the piston rod 29 passes. This valve housing is carried by a tubular member 44, the upper 55 end of which is split as at 45 and provided with a pair of lugs 46. This tubular member 44 is provided on its interior with a tapering annular shoulder 47, and said annular shoulder 47 is adapted to receive the 60 lower end of a tubular standard 48 to position said tubular standard as more clearly indicated by the reference character 49, said annular shoulder forming a support for said tubular standard.

65 Mounted within the lugs 46 is a shaft 50

and said shaft has one of its ends screw-threaded. Mounted upon the screw threaded end of said shaft is a nut and upon the other end of the shaft 50 there is an operating lever 51. By this construction it is 70 apparent that as the nut on the shaft 50 is tightened, the adjustment is made which permits the split end 45 of the tubular member 44 being clamped about the tubular standard 48 upon operation of the lever 51 75 on its screw threaded end of the shaft 50.

As more clearly shown in Figure 5, the tubular member 44 is provided with angularly disposed lugs 60, and pivotally mounted in the lugs 60 are dependent angularly 80 disposed arms 61. These arms 61 are each provided with hook extremities 62, and as more clearly shown in Fig. 1, the hook extremities 62 of these arms are adapted to engage over the upper edge 63 of the side of 85 the car to which the device is attached.

Projecting from the tubular member 44 is a web 64 and mounted in openings 65 in said web are arms 66. These arms 66 are adapted to engage openings 67 in webs 68 90 carried by the arms 61 in order that said arms may be adjusted about their pivotal point to meet various conditions in the size of the upper edges of the cars with which 95 they are adapted to engage.

Slidably mounted upon the tubular member 48 is a collar 70, and pivotally connected to said collar 70 as at 71, is a yoke 72. This yoke 72 is provided with a screw-threaded socket 73, and secured therein is 100 a supporting leg 74 of a suitable boom 75. To the upper end of this leg 74 is secured a housing 76, in which is mounted a pulley 77. The outer end of the boom 75 is pivotally connected as at 78, to the housing 76, 105 and the inner end of said boom 78 carries a yoke member 79, which is pivotally connected as at 80 to a collar or the like 91 mounted for free rotary movement upon the upper end of the tubular member 48. 110 Secured to the exterior of the tubular member 48 and rigidly connected thereto is a strap 92, and the lower end of the collar 91 carries a detachable ring 93 adapted to engage said strap 92 to prevent the collar 91 115 rising from the upper end of the tubular member 48. This ring 93 is secured in position by means of cap screws or the like 94.

Mounted in the yoke 79 is a pulley 81, 120 and said pulley is adapted to align with the pulley 77 heretofore mentioned. Secured to the yoke 79, as at 82, is a rope or cable 83, and said rope extends downwardly within the tubular member 48 about the pulley 80 125 and upwardly over the pulleys 81 and 77. The free end of this rope 83 is provided with a suitable grapple 84, by means of which the material to be loaded into the car or removed therefrom is grasped. While 130

in the present instance the material-handling means has been illustrated as a grapple, it is obvious that the same may be a bucket, sling, or other element suitable for operation upon the material to be handled.

The device operates in the following manner:

After the device has been positioned, the grapple 84 is engaged with the material, which in the present instance is illustrated as a railroad tie 90, which is to be elevated to a position where it can be placed in the car. After this has been done, the valve 35, to which the hose 40 is connected is rotated to permit air pressure to enter the cylinder 24. As this air enters the cylinder through the passage 38 and the check valve 36, the cylinder is forced downwardly, and through the medium of the cable 83 which passes around the pulley 30 carried by the piston, the grapple 84 is elevated to the position shown in Fig. 1.

After this has been done, the grapple is swung around to a position over the car and the three-way valve is again turned to permit of the exhaust of the air in the cylinder under the weight of the material elevated by the grapple 84. The air first exhausts through the opening 38 into the valve chamber 33, from whence it passes through the three-way valve 35 to the atmosphere. As the piston lifts within the cylinder to a position where it closes the passage 38, the air above the piston in the cylinder forms a cushion therefor. This air is then placed under compression which is bled through the port 37, thus allowing the piston to reach a position in the top of the cylinder. To further operate the mechanism it is only necessary to permit air to flow inwardly of the cylinder by a proper positioning of the three-way valve and the piston will again be depressed, as above described.

What is claimed is:

1. A device of the character described comprising a suitable supporting element, a cylinder telescoping within said element and adjustable with respect thereto, means carried by the supporting element and the cylinder for detachably attaching the device in operative position, a piston mounted in the cylinder, a tubular member carried by the upper end of said cylinder, and hoisting means carried by said tubular member and operated by the piston in the cylinder.

2. A device for loading and unloading cars comprising a cylinder, hoisting means operated by said cylinder, and means for attaching said cylinder to a car, said attaching means comprising a supporting hook carried by the cylinder and adapted to engage the top edge of the side of a car, an open-ended tubular member having a car-engaging hook, said open-ended tubular

member having telescopic engagement with the cylinder whereby car sides of different widths may be engaged, and means for preventing telescopic movement of the open-ended tubular member relative to the cylinder.

3. A mechanism for loading and unloading cars comprising a support consisting of a tubular member, a working cylinder mounted in said tubular member and adjustable with respect thereto, means for maintaining the adjustment between the support and the cylinder, means for detachably attaching the support in position on a car, means for detachably attaching the cylinder in position on a car, a piston movable in said cylinder, a tubular member supported in the upper end of said cylinder and extending vertically therefrom, a boom pivotally secured to the upper end of said last-mentioned member, and hoisting mechanism carried by said boom and connected to the piston in the cylinder whereby the hoisting mechanism will be operated upon movement of the piston within the cylinder.

4. In a loading and unloading mechanism, a support in the form of a tubular member, a cylinder telescoping within the tubular member and adjustable with respect thereto, means for maintaining the adjustment of the cylinder with respect to the tubular member, means for securing the tubular member and cylinder to a car, a tubular member mounted in the upper end of the first-mentioned tubular member, means for securing the second-mentioned tubular member against movement relative to the first-mentioned tubular member, a piston movable longitudinally of said cylinder, and hoisting mechanism supported on the second-mentioned tubular member and dependent upon the movement of said piston longitudinally of the cylinder for its operation.

5. A device for loading and unloading cars comprising a tubular support, a cylinder provided with rack teeth, said cylinder being mounted for telescoping engagement with the tubular support, a plurality of pawls adapted to engage the rack teeth of said cylinder to secure the same in adjusted position relative to the support, a piston operatively mounted in said cylinder, and hoisting means supported by said cylinder and adapted for movement in a horizontal plane thereabout and adapted to be operated by movement of the piston within the cylinder, substantially as described.

6. In a mechanism for loading and unloading cars, a support, a cylinder carried by said support, a valve housing comprising a tubular member having one of its ends adapted to receive the upper end of said cylinder and having its other end split, a hoisting mechanism received within the split end of the valve housing, and means for

- clamping the split end of the valve housing about the hoisting mechanism to secure the same in position relative to the valve housing and the cylinder.
7. In a mechanism for loading and unloading cars, a tubular support, a cylinder carried thereby, a valve chamber removably carried by the cylinder and having one of its ends split, a vertically extending standard received within the split end of the valve chamber, means for clamping the split end of the valve chamber about said vertically-extending standard, as and for the purpose set forth.
8. In a mechanism for loading and unloading cars, a tubular support, a cylinder carried thereby, a valve chamber removably carried by the cylinder and having one of its ends split, a vertically extending standard received within the split end of the valve chamber, means for clamping the split end of the valve chamber about said vertically-extending standard, and hoisting mechanism carried by said vertically extending standard and adapted for horizontal movement thereabout, as and for the purpose set forth.

loading cars, a tubular support, a cylinder carried thereby, a valve chamber removably carried by the cylinder and having one of its ends split, a vertically extending standard received within the split end of the valve chamber, means for clamping the split end of the valve chamber, about said vertically-extending standard, and hoisting mechanism carried by said vertically extending standard and adapted for horizontal movement thereabout, as and for the purpose set forth.

CHARLES E. LINDSAY.
CLINTON V. OGBIN.
